SPRING BALANCER

Edmund Peremi, Bayside, N. Y., assignor to
General Bronze Corporation, Garden City, N. Y.

Application September 6, 1949, Serial No. 114,205

9 Claims. (Cl. 16—197)

1

This invention relates to a spring balancer for exerting a substantially constant force on two spaced relatively movable objects as the objects are relatively moved toward or away from one another and is particularly adapted to be used as a window balancer for a slidable window sash. The present application is a continuation-in-part of my pending application, Serial No. 31,180, filed June 4, 1948, now Patent No. 2,604,655 issued July 29, 1952.

It is an object of the present invention to provide an improved spring balancer which will effectively balance the weight of a movable object in various positions of its movement. It is another object of the invention to provide an improved balancer of this type which comprises a single spring that exerts interrelated torsional and tensional forces upon the movable object and which, when used as a window balancer, will sustain the weight of a slidable sash in various positions of vertical adjustment of the sash. It is still another object of the invention to provide improved means for adjusting the torsion of the spring of such a balancer. Other objects of the invention will be in part obvious and in part pointed out hereafter.

The many objects and advantages of the present invention may best be appreciated and understood by reference to the accompanying drawings, which illustrate spring balancers incorporating several modifications of the present invention and wherein:

Figure 1 is a vertical sectional elevation of a spring balancer showing the general arrangement of the combined tension and torsion spring and the spiral actuator;

Figure 2 is a horizontal section taken on the line 2—2 of Figure 1 and showing the manner in which the spring is connected to the upper bracket;

Figure 3 is a horizontal section taken on the line 3—3 of Figure 4 and showing the interrelationship between the key-way and the spiral actuator;

Figure 4 is a right-hand elevation of the lower portion of the balancer showing the manner in which the lower end of the spring is secured in position;

Figure 5 is an enlarged vertical section of the lower portion of the balancer, similar to Figure 1, but showing further details of the balancer construction;

Figure 6 is a bottom plan view of the balancer of Figure 1 showing the pawl and ratchet device for adjusting the spring torsion;

2

Figure 7 is a vertical sectional elevation of a modified form of balancer;

Figure 8 is a horizontal section taken on the line 8—8 of Figure 7 and showing the manner of attachment of the spring to the upper bracket;

Figure 9 is a horizontal section taken on the line 9—9 of Figure 7 and showing the interrelationship between the key-way and spiral actuator in the embodiment of Figure 7;

10 Figure 10 is a horizontal section taken on the line 10—10 of Figure 11 and showing details of the spring torsion adjusting mechanism;

Figure 11 is an enlarged vertical section of the lower portion of the balancer of Figure 7 showing other details of the torsion adjusting mechanism;

Figure 12 is a vertical section taken on the line 12—12 of Figure 11, i. e., at right angles to Figure 11;

20 Figure 13 is a bottom plan view of the balancer shown in Figure 11;

Figure 14 is a vertical sectional elevation of still another modification of the balancer of Figure 1; and

25 Figure 15 is a bottom plan view of the modification of Figure 14.

Referring to the drawings and particularly to Figure 1, the balancer there shown comprises an upper bracket 10 having a hole 12 therein by means of which the balancer may be secured to a window frame by any suitable means such as a screw (not shown). At the lower end of the balancer, there is a second bracket 14 having a hole 16 therein by means of which the lower bracket 14 may be secured in any suitable manner to the window sash. Extending between the brackets 10 and 14 there is a combined tension and torsion spring 18 which is effectively connected at its ends to the two brackets respectively.

40 The upper end of spring 18 is rotatably secured to upper bracket 10 in the following manner. In the bottom of bracket 10 there is a hole 22 which receives a pin 20 having a head 24 of greater diameter than the hole 22. The head 24 has a peripheral under surface that rests on a washer 26 which is in turn supported by the bottom portion of bracket 10 in such manner that the pin 20 is rotatably mounted in the bracket. Secured to the lower portion of pin 20 by means

50 of a rivet 28 there is a downwardly extending tube or sleeve 30 which is located within the spring 18 and assists in maintaining proper axial alignment of the spring. At its upper end the tube 30 is provided with a pair of diametrically aligned vertical slots 32 (see also Figure 2). The

slots 32 extend somewhat below the bottom of pin 20 and thus define therewith a pair of holes through which the bent upper end 34 of the spring 18 is passed. Thus the upper end of the spring 18 is effectively secured to the tube 30 and pin 20, and through the pin 20 is mounted for rotation with respect to the bracket 10. The tube 30 and upper end of spring 18 are enclosed in an outer casing 36 which is fixed at its upper end to the bracket 10.

Referring now to Figure 5, as well as to Figure 1, extending into the tube 30 and centrally positioned therein is a spiral actuator 44 that cooperates with the tube in a manner persently to be described to rotate the tube and upper end of spring 18. Secured to the lower end of tube 30 there is a short sleeve 38 having inwardly projecting portions 39 which form a slot or key-way 42 through which the actuator 44 passes and which has a size and shape conforming with that of the cross-section of the actuator. The projections 40 of sleeve 38 engage the spiral surfaces of the actuator 44 to produce relative rotative movement of the tube and actuator as the actuator is moved axially with respect to the tube. The relationship between the actuator 44 and the projections 40 of sleeve 38 is best shown in Figure 3 of the drawings.

Still referring to Figure 5, the actuator 44 is effectively secured at its lower end to the bracket 14. Passing through the bracket 14 and rotatably mounted therein is a forked torsion adjusting pin 46 having a head 48 that engages the underside of bracket 14. The lower end of actuator 44 is positioned in the forked end of pin 46 and secured thereto by a rivet 50, which also serves to secure to the pin 46 a collar 52. The collar 52 and head 48 cooperate to limit axial movement of the pin 46 with respect to bracket 14 and the collar 52 also serves to ensure proper lateral positioning of the lower portion of spring 18.

Referring now to Figures 4 and 5, the bracket 14 is provided with a vertical spring-retaining member 54 having a vertical slot 56 therein. The lower end 58 of spring 18 is positioned near the bottom of slot 56 and a screw 60 is threaded into the slot to prevent, substantially, vertical movement of the lower end of the spring. Thus the lower end of the spring is effectively maintained in substantially fixed relation with respect to the bracket 14.

At the bottom of the balancer, mechanism is provided for adjusting the spring torsion. As best shown in Figure 6, the head 48 of adjusting pin 46 is provided with peripheral notches 62 to form a ratchet that is normally engaged by a pawl in the form of a resilient arm 64. The pawl 64 extends through a groove 66 in the underside of bracket 14 and (see Figures 1 and 4) terminates in an upwardly bent end 68 that is secured in a hole 70 of the bracket 14. The ratchet and pawl are normally urged into engagement by the torsion of spring 18. As shown in Figures 5 and 6, the head 48 has a kerf 72 in which a screw driver or other similar tool may be inserted to facilitate rotation of head 48 when it is desired to adjust the spring torsion. It is evident that rotation of head 48 will rotate the spiral actuator and tube 30, which in turn rotates the upper end of the spring. Since the lower end of the spring is fixed to bracket 14, rotation of the upper end of the spring varies the spring torsion.

As indicated in Figure 1, the spiral actuator is composed of two spiral sections that are wound in opposite sense. Thus the direction of the spiral

reverses at point 74 which is normally approximately at the mid-point of the actuator. The pitch of the spiral is a minimum at the ends of the actuator and becomes infinitely large at the point 74.

The operation of the device is as follows: The characteristics of spring 18 are normally so selected that the spring tension is approximately equal to one-half the weight of the window sash 10 (assuming that two balancers are used for each sash) when the sash is midway between its uppermost and lowermost positions. With the sash in its uppermost position, the spring is given a substantial pre-torsion. This torsion acts through tube 30 and projections 40 to exert on actuator 44 an upward force, herein referred to as the effective torsional force, which tends to support the weight of the sash.

As the bracket 14 is moved downwardly with the sash from its uppermost position, the tension of spring 18 increases proportionately to this downward movement. At the same time the tube 30 is rotated counter-clockwise (as viewed from above) with respect to actuator 44 and thus winds up the spring 18. Simultaneously the pitch of the spiral of the portion of the actuator engaging the key-way increases. The relationship between the parts is such that the effective torsional force decreases notwithstanding the increase in torsion of the spring. The pitch of the spiral is so selected that this decrease in effective torsional force is approximately proportional to the increase in spring tension due to downward movement of bracket 14.

When the actuator 44 engages the key-way 42 at point 74, the effective torsional force becomes zero and the sash is supported by tension of the spring alone. Thereafter, the direction of the spiral reverses and the effective torsional force 40 acts in a downward direction to reduce the tensile force exerted by the spring on the bracket 14 and window sash. Thus the net force that the spring exerts on the sash is maintained substantially constant throughout the range of movement of the sash. As described above, the torsion of the spring may be readily adjusted by rotating the head 48 of pin 46 with a screw driver or other suitable tool.

Referring now to Figures 7-13 of the drawings, a modified form of balancer is shown which is particularly useful with relatively small windows having relatively light weight sashes. The balancer of Figure 7 comprises a spiral actuator 80, spring 82, and tube 84, rotatably mounted in an upper bracket 86, all similar to the corresponding parts of the embodiment of Figure 1. The upper bracket 86 may be secured to a window frame in any suitable manner such as by means of the screw 88. The lower end of the tube 84 is crimped (see Figures 7 and 9) to form a slot or key-way 90 generally conforming with the shape of the cross-section of the spiral actuator and functioning in the same manner as the key-way 42 of Figure 1.

The principal difference between the embodiments of Figure 7 and Figure 1 is in the mechanism provided for adjusting spring tension. Still referring to Figure 7, the lower end of the balancer is secured by means of an L-shaped bracket 92 and a screw 94 to the window sash. The bracket 92 is in turn secured by the screw 96 to a plate 98 having an upset portion 100 forming a hook that engages a second hook 102 formed in the lower end of the spring 82. Thus the lower end of the spring is effectively secured

through hook 100, plate 98 and bracket 92 to the window sash.

Referring to Figures 11 and 12, the lower end of the actuator 80 extends through a hole 104 in the plate 98 and through a slot 105 of an adjusting button 106. The upper surface of button 106 normally bears against the underside of plate 98. At its lower extremity, the actuator 80 is provided with a pair of wings 108 that bear against the button 106 and cooperate therewith to limit upward movement of the actuator.

Surrounding the actuator just above the plate 98, there is a spring 110 which is under compression to urge the actuator upwardly. At its lower end spring 110 bears against a washer 112 which in turn bears against the upper surface of plate 98, whereas at its upper end spring 110 bears against a washer 114 that is held against upward movement by a pair of projections 116 formed on the actuator 80. Thus the spring 110 urges the actuator upwardly to the extent that upward movement is permitted by the adjusting button 106 and wings 108, and the button 106 is held resiliently against the lower surface of plate 98 by the spring.

As best shown in Figure 12, the plate 110 is swaged at two points to provide downward projections 118 that engage corresponding recesses 120 in the upper surface of adjusting button 106. The projections 118 and corresponding recesses 120 normally coat to prevent rotation of button 106 and actuator 80 with respect to plate 110. A kerf 122 is formed in the bottom of adjusting button 106 to receive a screw driver or similar tool. When it is desired to change the tension of spring 82, a suitable tool is inserted in the kerf 122 and the button 106 and actuator 80 rotated. It is apparent that as the button is rotated, spring 110 will be compressed slightly and the upper surface of the button will ride over the projections 118. The projections 118 and corresponding recesses 120 effectively provide a latch to maintain the desired adjustment of spring torsion. The balancing operation of the embodiment of Figures 7-13 is substantially similar to that of Figures 1-6 previously described.

Referring now to Figures 14 and 15 of the drawing, the embodiment there shown differs from those previously described in that the spring 130 is mounted in upper and lower spring adapters 132 and 134 respectively. The adapter 132 is rotatably mounted on upper bracket 136 by means of a rivet 138 and is provided with a peripheral groove 140 in which the upper end of spring 130 is secured. The lower adapter 134 is secured to a lower bracket 142 and is provided with a peripheral groove 144 in which the lower end of spring 130 is secured. The adapters 132 and 134 provide additional support for the ends of the spring in cases where such support is necessary or desirable.

The balancer of Figure 14 includes an actuator 146, similar to the actuators 44 and 80, which is secured at its lower end by means of a rivet 148 to an adjusting pin 150 rotatably mounted in the bracket 142. The pin 150 is provided with a head 152 which forms a ratchet that cooperates with a spring pawl 154, similar to the pawl 64. Pawl 154 extends through a groove in a stepped portion of bracket 142 and has an upturned end 158 secured in a hole 160 of a bracket 142. The operation of the balancer of Figures 14 and 15 is substantially similar to that of the embodiments previously described.

It is, of course, to be understood that the foregoing description is illustrative and various modifications may be made within the scope of the invention. As indicated at the beginning of the specification, the present balancer is not limited to use as a window balancer, but may also be used in other cases where it is desired to exert a substantially constant force on two relatively movable objects as they are moved toward or away from one another. In the description the terms "upper" and "lower" have been used for convenience. However, it is apparent that the present balancer is not necessarily used in a vertical position, but may also be located in a horizontal or other position as well. Also when the device is used as a window balancer, the bracket 14 or its equivalent may be secured to the window frame and the bracket 10 fixed to the sash.

While particular embodiments of the invention have been illustrated, it is to be understood that details of construction may be varied within the scope of the appended claims.

What is claimed is:

1. A balancer adapted to be connected to two relatively movable elements which are a window frame and a window sash slidable therein to balance the weight of said sash comprising in combination, a first and second spaced bracket adapted to be connected respectively to said two relatively movable elements, a tubular member mounted on said first bracket for axial rotation with respect thereto, a coiled spring effectively connected at one end to said tubular member and effectively connected at its other end to said second bracket, a torsion-adjusting member associated with said second bracket and mounted for rotation with respect thereto, a spiral actuator fixed at one end to said adjusting member and extending into said tubular member, said tubular member being provided with internally projecting portions forming a key-way engaged by said spiral actuator, and a detent on said bracket held in resilient contact with a portion of said torsion-adjusting member.

2. A balancer adapted to balance the weight of a window sash slidable in a window frame comprising in combination, a first and second spaced bracket adapted to be connected to said window frame and window sash respectively, a tubular member mounted on said first bracket for axial rotation with respect thereto, a coiled spring surrounding said tubular member and spaced therefrom, one end of said spring being connected to said tubular member near its point of attachment to said first bracket and the other end of said spring being effectively connected to said second bracket, a torsion-adjusting member associated with said second bracket and mounted for rotation with respect thereto, a spiral actuator fixed at one end to said adjusting member and extending into said tubular member, said tubular member being provided with internally projecting portions forming a key-way engaged by said spiral actuator, and a detent on said bracket held in resilient contact with said torsion-adjusting member said spiral actuator comprising two spiral sections wound in opposite sense.

3. A spring balancer adapted to be connected to two relatively movable elements which are a window frame and a window sash slidable therein to balance the weight of said sash comprising in combination, a first and second spaced bracket adapted to be connected respectively to said two relatively movable elements, a tubular member mounted at one end on said first bracket for axial

rotation with respect thereto, a coiled spring surrounding said tubular member and spaced therefrom, one end of said coiled spring being connected to said tubular member near its point of attachment to said first bracket and the other end of said coiled spring being effectively connected to said second bracket, a torsion-adjusting pin rotatably mounted in said second bracket and a spiral actuator fixed at one end to said adjusting pin and extending through said spring and into said tubular member, said tubular member being provided with internally projecting portions to form a key-way engaged by said spiral actuator said adjusting pin having a ratchet portion and said second bracket having a pawl mounted thereon and engaging said ratchet portion of the adjusting pin.

4. A balancer adapted to be connected to two relatively movable elements which are a window frame and a window sash slidable therein to balance the weight of said sash comprising in combination, a first and second spaced bracket adapted to be connected respectively to said two relatively movable elements, a tubular member mounted at one end on said first bracket for axial rotation with respect thereto, a coiled spring surrounding said tubular member and spaced therefrom, one end of said spring being connected to said tubular member near its point of attachment to said first bracket and the other end of said spring being effectively connected to said second bracket, a torsion-adjusting pin rotatably mounted in said second bracket, a collar fixed to said adjusting pin and located within said other end of said spring to position it, a spring-retaining member mounted on said second bracket to retain said other end of said spring in fixed relation with respect to said bracket independently of movement of said adjusting pin, a spiral actuator fixed at one end to said adjusting pin and extending into said tubular member, said tubular member being provided with internally projecting portions forming a key-way engaged by said spiral actuator said adjusting pin having a ratchet portion and said second bracket having a pawl mounted thereon and engaging said ratchet portion.

5. A balancer for slidable window sash which includes a tube having a key-way at its lower end, a coil spring secured to said tube and surrounding said tube, means securing the other end of said spring to a window sash, a spiral actuator attached to said sash and extending through said key-way into said tube, a bracket adapted to be secured to a window frame, a spring adapter secured to the upper end of said tube, a shaft rotatably supporting said adapter and tube on said bracket, and means preventing the rotation of said actuator.

6. A balancer for slidable window sash which includes a tube having a key-way at its lower end, a coil spring secured to said tube at one of its ends and surrounding said tube, means securing the other end of said spring to a window sash, a spiral actuator attached to said sash and extending through said key-way into said tube, means rotatably supporting the upper end of said tube and spring, a bracket adapted to be secured to said window sash, a pin rotatably adjustable in said bracket, a spring adapter surrounding said pin, means for securing said pin, adapter, and the lower end of said actuator together, and means for maintaining said pin in various positions of adjustment.

7. A balancer adapted to be connected to two

relatively movable elements which are a window frame and a window sash slidable therein to balance the weight of said sash comprising in combination, a first and second spaced bracket adapted to be connected respectively to said two relatively movable elements, a tubular member mounted at one end on said first bracket for axial rotation with respect thereto, a coiled spring surrounding said tubular member and spaced therefrom, one end of said spring being connected to said tubular member near its point of attachment to said first bracket and the other end of said spring being effectively connected to said second bracket, and a spiral actuator effectively secured at one end to said second bracket and extending into said tubular member, said tubular member being provided with internally projecting portions forming a key-way engaged by said spiral actuator, torsion-adjusting means interposed between said spiral actuator and said second bracket for adjusting the torsion of said spring, said torsion-adjusting means comprising a torsion-adjusting pin rotatably mounted in said second bracket and connected to said spiral actuator, a ratchet formed on one end of said adjusting pin and a pawl mounted on said second bracket and resiliently engaging said ratchet portion.

8. A balancer adapted to be connected to two relatively movable elements which are a window frame and a window sash slidable therein to balance the weight of said sash comprising in combination, a first and second spaced bracket adapted to be connected respectively to said two relatively movable elements, a tubular member mounted at one end on said first bracket for axial rotation with respect thereto, a coiled spring surrounding said tubular member and spaced therefrom, one end of said spring being connected to said tubular member near its point of attachment to said first bracket and the other end of said spring being effectively connected to said second bracket, and a spiral actuator effectively secured at one end to said second bracket and extending into said tubular member, said tubular member being provided with internally projecting portions forming a key-way engaged by said spiral actuator, torsion-adjusting means interposed between said spiral actuator and said second bracket for adjusting the torsion of said spring, said torsion-adjusting means comprising a member fixed to the spiral actuator and having a recess, a projection formed on said second bracket and normally engaging said recess and spring means for urging said projection into said recess.

9. A balancer as claimed in claim 8 and wherein the spring means is an auxiliary coiled spring surrounding the spiral actuator and effectively fixed thereto at one end and bearing at its other end against said second bracket.
